No. 703,890.

Patented July 1, 1902.

J. BREJCHA & E. SCHULTE.
ROCK BORING MACHINE.

(Application filed Jan. 18, 1901.)

UNITED STATES PATENT OFFICE.

JOSEF BREJCHA, OF STRASBURG, AND EDUARD SCHULTE, OF DUSSELDORF,
GERMANY.

ROCK-BORING MACHINE.

SPECIFICATION forming part of Letters Patent No. 703,890, dated July 1, 1902.

Application filed January 19, 1901. Serial No. 43,945. (No model.)

To all whom it may concern.

Be it known that we, JOSEF BREJCHA, a resident of Strasburg, and EDUARD SCHULTE, a resident of Dusseldorf, Germany, subjects 5 of the Emperor of Germany, have invented an Improvement in Rock-Boring Machines, of which the following is a specification.

Our invention resides in the features and combinations of features hereinafter fully described, and particularly pointed out in the 10 claims.

In the drawings, Figure 1 is a central vertical section of the invention. Fig. 2 is a side view of the same. Fig. 3 is a section of Fig. 15 1 on line A B. Fig. 4 is an end view looking from the left of Fig. 1.

In the drawings, *k* is a cylinder arranged to rotate in bearings *l m*, supported by brackets *n o* from a base *p*. This cylinder may be rotated in any suitable way, as by the gearing *q*, Fig. 1. Within this cylinder a piston *f* is arranged to slide, carrying a hollow piston-rod *d*, which projects out of the rear end of the cylinder.

25 Rotary motion is imparted to the hollow piston-rod by a coupling block or piece *w*, Fig. 3, which is formed to fit flat surfaces *v* on the outer side of the hollow piston.

A hand-wheel *i* is fixed to the rear end of 30 the rotary cylinder, by which it may be turned. Within the hollow piston-rod is a hollow boring-rod *a*, connected at its front end with the boring-tool *b* and at its rear end with the end of the hollow piston-rod *d* by means of a screw- 35 plug *c*, which engages interior threads on the boring-rod and is fixed by a screw-thread to a cap *g*, which cap is connected to the piston-rod *d* by a pin *h*.

The bearing *l* is provided with valves *r* and 40 *u*, controlling the inlet and outlet of water to and from the pressure-space *s* within the rotary cylinder and surrounding the hollow piston-rod, the pressure in which space acts upon the piston-head *f*.

45 A space is left at *e* between the hollow piston-rod *d* and the boring-rod, and a port *t* leads from the space *s* to this space *e*, while another

port *x* leads from the said space *e* to the interior of the hollow boring-rod; and thus the water is free to pass to the working parts, keeping them cool, and disintegrate the material bored.

When the piston *f* has moved all the way forward, the hollow piston-rod and the boring-rod may be uncoupled at their rear ends, and 55 then by connecting a new length of rod with the rear end of the length which has been advanced and still holds the boring-tool the operation of boring may be continued, it being understood that the piston *f* is now retracted, 60 so that the rear end of the piston-rod can be connected with the rear end of the new length of the boring-rod, it being understood also that this new length, besides having a screw-threaded front end to fit into the rear end of 65 the original length of boring-rod, has also an interior screw-thread at its rear end to receive the screw-plug *c*.

We claim—

1. In combination in a boring-machine, a 70 boring-rod *a*, a cylinder *k*, a piston-head *f* within the said cylinder, a piston-rod *d* connected to the piston and within which the boring-rod is located and a connection between the hollow piston-rod and the boring-rod, said connection being detachable and outside the rear end of the cylinder, substantially as described. 75

2. In combination in a boring-machine, a boring-rod, a cylinder *k*, a piston-head *f* within the said cylinder, a piston-rod *d* connected 80 to the piston and within which the boring-rod is located and a connection between the hollow piston-rod and the boring-rod, said connection comprising the head *g*, the pin *h* and the screw-plug *c*, substantially as described. 85

3. In combination, the rotary cylinder, the piston and hollow piston-rod therein, the boring-rod within the hollow piston-rod, a coupling-nut *w* between the rotary cylinder and the hollow piston-rod to turn the latter and a 90 connection between the hollow piston-rod and the boring-rod, said connection comprising the screw-plug *c*, engaging the inner rear end of the boring-rod, substantially as described.

4. In combination, a cylinder *k*, means for rotating the same, a piston *f* working within and in contact with the cylinder, a hollow piston-rod, a boring-rod within the hollow piston-rod, a connection between the hollow piston-rod and boring-rod and a connection between the cylinder and hollow piston-rod comprising the nut *w* having portions to engage flat parts on the hollow piston-rod, said nut being connected to the cylinder, substantially as described.

In witness whereof we have hereunto set our hands in presence of two witnesses.

JOSEF BREJCHA.
EDUARD SCHULTE.
